UNITED STATES PATENT OFFICE.

HUGH J. DYKES, OF BERKELEY, CALIFORNIA.

RAILWAY-SPIKE.

No. 874,055.

Specification of Letters Patent.

Patented Dec. 17, 1907.

Application filed February 9, 1907. Serial No. 366,544.

To all whom it may concern:

Be it known that I, HUGH J. DYKES, a citizen of the United States, residing at Berkeley, in the county of Alameda and State of California, have invented certain new and useful Improvements in Railway-Spikes, of which the following is a specification.

My invention relates to the class of railway spikes.

10 The general objects of my invention may be, briefly, stated to be to provide a wedging action on the rail in driving the spike, a maximum bite in the wood into which the spike is driven, and a positive, permanent engagement between the rail and the spike when the latter is driven home.

To these ends my invention consists in the novel construction of the spike, which I shall, hereinafter, fully describe.

20 Referring to the accompanying drawings, Figure 1 is a section of a rail and cross-tie, showing the spikes in side elevation. Fig. 2 is a perspective view of the spike, taken from the back. Fig. 3 is a similar view from the 25 front.

The spike 1 has a flanged or peak-head 2. From the head the spike body has a general inclination outwardly or backwardly, so that its point 3 lies in a vertical plane back of the 30 head.

The back of the spike body, from the back of the head, is curved to or nearly to its point, as is indicated by $x-x$, on an arc or arcs taken from a center or centers back of the 35 spike, so that, for convenience, the back of the spike may be termed concave.

Under the front or peak of the spike-head is formed a throat 4, and from the lower wall of this throat, the front of the spike, down to 40 a short distance from the point, is a straight plane, as is indicated by $y-y$, and thence the front is curved to the point.

In driving the spike, its point is first set up against the flange 5 of the rail 6, and the 45 spike is driven into the tie 7. As it is driven down, the straight front $y-y$ of the spike hugs the edge of the flange, with constantly increasing pressure; for, on account of the general outward or backward inclination of 50 the spike-body, it is forced, at an outward angle, into the wood, its curved back increasing this effect and augmenting its bite in the wood, until, when driven home, the spike finally springs its throat 4 into a close 55 embrace upon and against the rail-flange, the whole spike assuming the position shown

in Fig. 1. This is true with regard to one spike; and it will readily be seen that the opposite spike when driven, will have the effect of clamping the rail-flange between 60 the two spikes with what may be termed a wedging pressure.

To remove the spike, it is forced back by the insertion of the point of a crow-bar between the peak-edge of the head 2 and the 65 web of the rail, thereby relieving its throat from the rail-flange; whereupon the spike can be withdrawn.

For such spikes as have to engage the rails at the fish-plates or connections between 70 rails, the throat 4 will, of course, be made wide enough to embrace the foot of such plates or connections, in addition to the rail-flange.

By the use of a spike, shaped as I have described, there result these marked advantages, namely, a driving of the spike with a wedging action; a firm bite on the wood; and a secure and positive engagement, by reason of the throat, with the rail-flange, which last 80 named result will cause the rail and spike to remain together, the spike rising with the rail, and being forced down again with it; thereby avoiding the separation which takes place when the ordinary spike, after rising 85 with the rail, remains raised, when the rail is depressed. Also, the shape of the spike I have described, is such that even when its bite is partially loosened by the working of the rail, the loose area of its seat is a minimum one, requiring for its extension, substantially as much pressure as that which first loosened it.

Having thus described my invention, what I claim as new and desire to secure by Letters 95 Patent is,

A railway-spike having a flanged head with an underlying throat to embrace the rail-flange, and a body inclined backwardly from said head, the back of the body being concave 100 in the direction of and substantially throughout its length, and its front, from the lower wall of the throat, being a straight plane down to the vicinity of its point, and thence curved to said point.

In testimony whereof I have signed my name to this specification in the presence of two subscribing witnesses.

HUGH J. DYKES.
